UNITED STATES PATENT OFFICE.

WILLIAM SHERMAN BROWN, OF KNOXVILLE, TENNESSEE.

STEAM-ENGINE VALVE-GEAR.

1,110,287.

Specification of Letters Patent.

Patented Sept. 8, 1914.

Application filed August 14, 1913. Serial No. 784,735.

To all whom it may concern:

Be it known that I, WILLIAM SHERMAN BROWN, a citizen of the United States, residing at Knoxville, in the county of Knox and State of Tennessee, have invented a new and useful Improvement in Steam-Engine Valve-Gear, of which the following is a specification, reference being had to the accompanying drawing.

10 My improvement relates particularly to mechanism for transmitting motion from the crank of a drive wheel of a steam locomotive to the distributing valve which admits steam to the cylinder.

15 The object of the improvement is to provide a construction which is simple, has the parts accessibly located, and avoids irregularity of valve action due to lost motion or "pounding" at the crank.

20 This improvement is a modification of the mechanism described by my United States Patent No. 1,033,082, granted July 23, 1912, for "steam-engine valve-gear".

In the accompanying drawings, Figure 1 is a side elevation, portions being broken away, showing my improvement applied to one side of a locomotive; Fig. 2 is a plan of a portion of the mechanism shown by Fig. 1; Fig. 3 is a section on the line 3-3, of Fig. 1 looking toward the right, the slide-block being in its middle position; Fig. 4 is a section on the line, 4-4, of Fig. 1 looking toward the right; Fig. 5 is a plan of a bridge; Fig. 6 is a side elevation of said bridge.

25 Referring to said drawings, 1, is the usual valve stem extending to the distributing valve (not shown). The usual horizontal, parallel cross-head guide bars, 2, are supported at their rear ends by the guide yoke extension, 3. The usual connecting rod or pitman, 4, is coupled to the usual main crank, 5, carried by a drive wheel, D. On the main crank, 5, is rigidly mounted a first auxiliary crank, 6, standing 90 degrees forward of the main crank. On said first auxiliary crank is a second auxiliary crank, 7, standing 90 degrees back of the first auxiliary crank and on the radius of the main

50 crank.

A bridge, B, is located above the frame, A, and extends from the ordinary guide-yoke, 8, and guide-yoke extension, 3, to the cross-beam or plate, 10, and is secured to

said guide yoke and to said cross-beam by 55 means of bolts, 9. Said bridge is in the form of a plate having its length horizontal and being turned to bring its long edges into an upright plane. At its rear end, the bridge has a lateral extension, 11, resting 60 against the cross-beam, 10, and receiving said bolts, 9. At its forward end the bridge has a transverse extension, 12, reaching to both sides of the body of the bridge and resting against the guide yoke, 8, and the 65 guide yoke extension, 3, and receiving said bolts, 9. The innermost of said bolts extend through the transverse extension, 12, and the guide yoke, 8, while the others of said bolts extend through said member and 70 through the guide yoke, 8, and the guide yoke extension, 3.

On the outer portion of the transverse member, 12, and integral therewith is an ear, 13, which is directed rearward; and on the inner portion of said transverse member is another ear, 14, also directed rearward and located horizontally opposite the ear, 13. Each of said ears has a bearing, 15, receiving the ends of a shaft, 16. On said 80 shaft is a bell crank or rocking member, F, preferably rotatable on said shaft, the latter being held immovably in its bearings. Said bell crank has an approximately horizontal arm, 17, and a depending arm, 18. 85

On the upper edge of the bridge, B, are horizontal bosses, 20. A segment, E, has at each end a foot, 21, resting upon one of the bosses, 20; and bolts, 22, extend through said feet and said bosses and secure said 90 segment rigidly upon the bridge, B. Said segment is in the form of a plate having its body set in an upright plane. In said segment is a curved slot, 23, in which rests a slide block, 24, to which is coupled the 95 upper end of an approximately upright link. 25. The lower end of said link is coupled to the forward end of the first auxiliary pitman rod, 26, by a bolt, 27. The rear end of said pitman rod is coupled to the first auxiliary crank. The slot, 23, is preferably made concentric with an axis which approximately intersects a line which is an extension of the cylinder axis and cuts the axis of the drive wheel, D; and the length of 100 said link, 25, is such as to allow the axis of said bolt, 27, to be coincident with the axis to which said slot is concentric. An ap-

proximately horizontal auxiliary reach rod, 28, is coupled by its forward end to the slide block, 24, and by its rear end to the arm, 29, which is rigid on a rock shaft, 30, supported in bearings, 31. On said rock shaft is an arm, 32, to which is coupled a reach rod, 33, which is in turn coupled to the ordinary reversing lever, 34, working on a sector or quadrant, 35. A second auxiliary pitman rod, 36, has its rear end coupled to the second auxiliary pitman, 7, while its forward end is coupled to the lower arm, 37, of a rocking member, G, which is coupled to the depending arm, 18, of the rocking member or bell crank, F. The forward end of the second auxiliary rod is forked and extends to each side of the arm, 37, and receives a bolt, 38, which also extends through the arm, 37. The rocking member, G, consists of said arm, 37, a journal, 39, and an arm, 40, extending upward, and a wrist, 41, on said arm. The journal, 39, rests in a horizontal bearing on the lower end of the arm, 18; and the arm, 37, extends downward while the arm, 40, extends upward, so that when the lower end of the arm, 37, is moved forward, the upper end of the arm, 40, will be moved backward and vice versa.

30 The bell crank or rocking member, F, may be regarded as a moving member, and the auxiliary rocking member, G, may be regarded as a moving member mounted upon and movable upon the other moving member. The bell crank may be regarded as the first of said moving members while the rocking member is regarded as the second of said moving members.

An approximately upright link, 19, has 40 its upper end coupled to the arm, 17, of the bell crank, while its lower end is coupled to the forward end of the first auxiliary rod, 26. The link, 19, and the link 25, are preferably coupled to the first auxiliary rod on 45 the same horizontal axis, and such construction is shown by the drawings, the lower end of said links extending into a fork on the forward end of said auxiliary pitman rod. The link, 25, has a wrist, 43, extending into 50 the link, 19, and a bolt, 27, extends through the fork and said wrist. The link, 19, is at the inner side and is coupled to the arm, 17, of the bell crank by means of a wrist, 44, rigid on said link and extending into a horizontal bearing, 45, on the arm, 17, said wrist extending through said bearing and receiving on its end a nut, 46. The link, 25, is forked at its upper end and extends to each side of the slide block, and a bolt, 47, extends horizontally through said link and said block.

The segment, E, and the bell crank, F, are so placed relative to each other as to bring the axis of the bearing, 45, of the arm, 17, into the middle of the segmental slot, 23,

so that the upper axes of oscillation of the links, 19 and 25, will coincide whenever the slide block is put upon the center by means of the reversing lever. This involves making the two links of the same length.

In operation, the slide block, 24, is set in any desired position in the slot, 23, by means of the reversing lever, and while said block is so set, the link, 25, oscillates on said block with each reciprocation of the first auxiliary pitman rod, the axis of the bolt, 27, moving in an arc in which lies the axis to which the slot, 23, is concentric; and the distance between the wrist of the said first auxiliary crank and the bolt, 27, is such as to bring the axis of said bolt into the slot axis when the drive wheel is on either the front or the rear center. In Fig. 1, the drive wheel is shown on the rear center, the auxiliary crank being on the top. When the slide block is on the center of the segment, E, and the upper axis of the link, 25, is in alignment with the upper axis of the link, 19, said two links oscillate in unison on such axis during the reciprocation of the first auxiliary pitman rod, without moving the arm, 17. But when the slide block is moved forward of said center, as shown in the drawings, the link, 25, will oscillate on said block, the lower end being raised and lowered in an arc path which is concentric to the axis of the slide block. Since the lower end of the link, 19, is secured for movement with the lower end of the link, 25, and the upper end of the link, 19, is so joined to the arm, 17, of the bell crank as to permit only up and down movement, the reciprocation of the first auxiliary pitman rod at such time causes up and down movement of the link, 19. The range of such movement depends upon the distance of the slide block from the middle of the segment.

The upper axes of the links, 25 and 19, may be at different elevations, if it be deemed permissible to allow some movement of the bell crank when the reversing mechanism is on its center. If such difference in elevation of said axes is increased more and more, such movement of the bell crank while the reversing mechanism is on its center will be increased more and more. Manifestly, only a small movement of the bell crank at such time is permissible, and the ideal construction brings no movement of the bell crank at such time.

The drive wheel and the axle being joined rigidly and moving in unison, it is immaterial whether the main crank is secured to the axle or said wheel.

I claim as my invention:

1. In a steam engine valve gear, the combination of a valve stem, a rocking member connected with said stem, means for bodily moving said rocking member forward and backward, and other means in operative re-

- lation with the outer side of a drive wheel for rocking said rocking member, substantially as described.
2. In a steam engine valve gear, the combination of a valve stem, a rocking member connected with said stem, means in operative relation with a drive wheel for bodily moving said rocking member forward and backward, and other means also in operative relation with the outer side of a drive wheel for rocking said rocking member, substantially as described.
3. In a steam engine valve gear, the combination of a valve stem, a first movable member, means in operative relation with the outer side of a drive wheel and with said movable member for moving the latter, a second movable member on said first movable member and connected with the valve stem, and means also in operative relation with a drive wheel and with said second movable member for moving the latter, substantially as described.
4. In a steam engine valve gear, the combination of a valve stem, a rocking member connected with said stem, means in operative relation with a drive wheel and reversing mechanism for variably bodily moving said rocking member forward and backward, and other means also in operative relation with a drive wheel and with said rocking member for rocking the latter, substantially as described.
5. In a steam engine valve gear, the combination of a valve stem, reversing mechanism, a rocking member connected with said stem, means in operative relation with said reversing mechanism for bodily moving said rocking member forward and backward, and other means in operative relation with the outer side of a drive wheel for rocking said rocking member, substantially as described.
6. In a steam engine valve gear, the combination of a valve stem, reversing mechanism, a rocking member connected with said stem, means in operative relation with a drive wheel and said reversing mechanism for bodily moving said rocking member forward and backward, and other means also in operative relation with the outer side of a drive wheel for rocking said rocking member, substantially as described.
7. In a steam engine valve gear, the combination of a valve stem, reversing mechanism, a first movable member, means in operative relation with a drive wheel and said reversing mechanism and said movable member for moving the latter, a second movable member mounted on said first movable member and connected with the valve stem, and means also in operative relation with a drive wheel and with said second movable member for moving the latter, substantially as described.
8. In a steam engine valve gear, the combination of a valve stem, a bell crank, reversing mechanism, means in operative relation with said reversing mechanism for rocking said bell crank, a movable member mounted on said bell crank and connected with the valve stem, and means in operative relation with a drive wheel for moving said movable member, substantially as described.
9. In a steam engine valve gear, the combination of a valve stem, a bell crank, means for rocking said bell crank, a movable member mounted on said bell crank and connected with the valve stem, and means in operative relation with a drive wheel for moving said movable member, substantially as described.
10. In a steam engine valve gear, the combination of reversing mechanism, a first movable member, a valve stem, an auxiliary crank, an auxiliary rod coupled to said crank, two approximately upright links each having its lower end coupled to the auxiliary rod and one having its upper end coupled to said reversing mechanism and the other having its upper end in operative relation with said first movable member, a second movable member mounted on said first movable member in operative relation with the valve stem, and means in operative relation with a drive wheel and said second movable member, substantially as described.
11. In a steam engine valve gear, the combination of reversing mechanism, a valve stem, a bell crank, an auxiliary crank, an auxiliary rod coupled to said crank, two approximately upright links each having its lower end coupled to the auxiliary rod and one having its upper end coupled to said reversing mechanism and the other having its upper end coupled to said bell crank, a second movable member mounted on said bell crank and in operative relation with the valve stem, and means in operative relation with a drive wheel and said movable member, substantially as described.
12. In a steam engine valve gear, the combination of an approximately horizontal bridge-piece, reversing mechanism, a first movable member, a valve stem, an auxiliary crank, an auxiliary rod coupled to said crank, two approximately upright links each having its lower end coupled to the auxiliary rod and one having its upper end coupled to said reversing mechanism and the other having its upper end in operative relation with said first movable member, a second movable member mounted on said first movable member and in operative relation with the valve stem, and means in operative relation with a drive wheel and said second movable member, substantially as described.
13. In a steam engine valve gear, the combination of an approximately horizontal bridge-piece, reversing mechanism, a first

movable member, a valve stem, a bell crank, an auxiliary crank, an auxiliary rod coupled to said crank, two approximately upright links each having its lower end coupled to the auxiliary rod and one having its upper end coupled to said first movable member and the other having its upper end coupled to the bell crank, a second movable member mounted on said bell crank and in operative relation with the valve stem, and means in operative relation with a drive wheel and said second movable member, substantially as described.

14. In a steam engine valve gear, the combination of a valve stem, a slide block, means for moving said block, an auxiliary crank, an auxiliary rod coupled to said crank, a first movable member, two approximately upright links each having its lower end coupled to the auxiliary rod and one having its upper end coupled to said slide block and the other having its upper end in operative relation with said movable member, a second movable member mounted on said first movable member and connected with the valve stem, and means in operative relation with a drive wheel for moving said second movable member, substantially as described.

15. In a steam engine valve gear, the combination of a valve stem, a slide block, means for moving said block, a bell crank, a movable member mounted on said bell crank and connected with the valve stem, an auxiliary crank, an auxiliary rod coupled to said crank, two approximately upright links each having its lower end coupled to the auxiliary rod and one having its upper end coupled to said slide block and the other having its upper end coupled to said bell crank, and means in operative relation with a drive wheel for moving said second movable member, substantially as described.

16. In a steam engine valve gear, the combination of a valve stem, an approximately horizontal bridge-piece forming a slide way, a slide block on said slide way, means for moving said slide block, a first movable member, a second movable member mounted on said first movable member and

connected with the valve stem, an auxiliary crank, an auxiliary rod coupled to said crank, two approximately upright links each having its lower end coupled to the auxiliary rod and one having its upper end coupled to said slide block and the other having its upper end in operative relation with said first movable member and means in operative relation with a drive wheel for moving said second movable member, substantially as described.

17. In a steam engine valve gear, a combination of a valve stem, an approximately horizontal bridge-piece forming a slide way, a slide block on said slide way, means for moving said slide block, a bell crank, a movable member mounted on said bell crank and in operative relation with the valve stem, an auxiliary crank, an auxiliary rod coupled to said crank, two approximately upright links each having its lower end coupled to the auxiliary rod and one having its upper end coupled to the slide block and the other having its upper end coupled to the bell crank, and means in operative relation with a drive wheel for moving said movable member, substantially as described.

18. In a steam engine valve gear, the combination of a valve stem, a bracket, a bell crank hinged to said bracket, a movable member mounted on said bell crank and in operative relation with the valve stem, a slide block, means for supporting said slide block, an auxiliary crank, an auxiliary rod on said auxiliary crank, two approximately upright links each having its lower end coupled to said auxiliary rod and one having its upper end coupled to said slide block and the other having its upper end coupled to said bell crank, and means in operative relation with a drive wheel for moving said movable member, substantially as described.

In testimony whereof I have signed my name, in presence of two witnesses.

WILLIAM SHERMAN BROWN.
